[57] CLAIM

The ornamental design for a shoe outsole, as shown and described.

DESCRIPTION

FIG. 1 is a perspective view of a shoe outsole showing my new design;

FIG. 2 is a bottom plan view thereof;

FIG. 3 is a front elevational view thereof;

FIG. 4 is a rear elevational view thereof;

FIG. 5 is a side elevational view of one side thereof; and,
FIG. 6 is a side elevational view of the other side thereof.
The broken line showing of a shoe upper and part of the sole
in FIGS. 1-6 is for illustrative purposes only and forms no
part of the claimed design.
